UNITED STATES PATENT OFFICE

LOUIS LARSON, OF KATONAH, NEW YORK

DESIGN FOR A PET'S BED

Application filed January 25, 1933. Serial No. 46,974. Term of patent 14 years.

To all whom it may concern:

Be it known that I, LOUIS LARSON, a citizen of the United States, residing at Katonah, in the county of Westchester and State of New York, have invented a new, original, and ornamental Design for a Pet's Bed, of which the following is a specification, reference being had to the accompanying drawing, forming part thereof.

The figure is a perspective view of a pet's bed, showing my new design.

I claim:

The ornamental design for a pet's bed, as shown.

LOUIS LARSON.
